UNITED STATES PATENT OFFICE.

GEBHARD JAEGER AND JOSEPH EGGERT, OF COLUMBUS, OHIO, ASSIGNEES TO THE JAEGER MACHINE COMPANY, OF COLUMBUS, OHIO, A CORPORATION OF OHIO.

DRUM FOR CONCRETE-MIXING MACHINES.

Application filed February 10, 1928. Serial No. 253,313.

This invention relates to concrete mixing devices of the rotating and tilting variety, that has a single opening for the reception and discharge of the concrete forming material, the object of the invention being to provide a mixing device or drum of improved construction, whereby the mixing of the fine and coarse material is more rapidly and thoroughly performed than hitherto.

The invention is embodied in the construction and combination of features shown in the accompanying drawing and set forth in the following description and claims.

15 In said drawing:

Figure 1 is a perspective view looking into the interior of the drum.

Figure 2 is a combined side elevation and central section of the drum.

20 Figure 3 is a view in side elevation showing the drum mounted on a standard and in normal mixing position, preparatory to discharging the mixed contents.

The body of the drum is constructed with 25 a frusto-conical upper wall 5, fixed to a bowl portion having oppositely curved walls 6, 6, and opposite flat walls 7, 7, joined to said walls 6, 6, and a diametrical bottom portion 8, thereby forming four corners 30 in the side of the bowl between said flat and curved portions. The flat walls 7, 7, form in effect a peculiar interruption of the continuity of the otherwise curved surface of the bowl and if the drum be rotated while 35 its axis is at an angle to the vertical, as for example as seen in Fig. 3, the movement of the material is alternately retarded and speeded by the flat and curved surfaces respectively of the bowl.

40 Cooperating with the peculiar form of said walls of the bowl are two blades, each composed mainly of two parts, to-wit: an outer part or blade 9 of relatively wide trapezoidal form, roughly, and a long narrow blade, 10, secured thereto and extending therefrom toward the bowl of the drum. The larger part, 9, of the blade is affixed to the wall of the drum to stand at an angle of approximately 30° to the plane of the 45 axis of the drum, and its corner next the wall and mouth of the drum is bent inward, as seen at 9a, in the direction of the normal direction of motion of the drum; and the narrow blade 10 is secured to stand nearly 50 parallel to the wall of the drum and it is

curved forwardly in the direction of its motion from the point of its connection with the blade 9, all as best seen in Fig. 1. The said blades are secured to the interior drum by means of brackets, as shown at 11 and 12, bolted to the blade and drum.

The drum is supported upon a yoke 13 having a spindle fixed on the yoke that enters a tubular bearing 14 rising from the center of the bottom of the drum. This yoke 15 has at its opposite ends trunnions that are journaled in standards 15 so that by swinging the yoke the drum can be oscillated or tilted as by handles 16 connected with one of the trunnions to different positions for supplying 20 the materials to the drum, mixing and discharging the same. The drum is also provided with a circumferential rack 17 engaged by a pinion 18 to impart a rotary motion to the drum. The tilting and rotary 25 motions of the drum are effected independently of each other. The construction in respect of the means for tilting and rotating the drum in various forms are well known in the art and require no further detailing here.

In practice the drum is kept rotating and is supplied with the materials to be mixed when the drum is swung to a suitable position opposite that appearing in Fig. 3. The drum is then slowly swung over to approximately the horizontal position shown in Fig. 3, in which position the principal mixing operation takes place. In this position the material is moved back and forth with reference to the mouth and bowl of the drum. 30 In this mixing operation, the concrete material is carried in the lower portion of the drum (in the substantially horizontal position) in a general way with the motion of the drum, the flat surfaces of the bowl tending to retard and push the mass of the material towards the mouth of the drum, and the material being lifted by the narrow and wide portions of the blade. When sufficiently elevated, the material slides off the wide portion of the blade back again toward the lower side of the bowl, and when the material slides from such larger portion of the blade it falls mostly upon the wall of the drum in advance of the oncoming opposite blade. The effect on the moist materials is a kneading, stirring and swirling operation due to the cooperation of the peculiar form of the blades with the form 35 of the bowl, and, of course, when in the sub-

stantially horizontal position of the drum. The central journaling stem of the drum co-operates more or less in dividing and mixing the materials, especially when the material slides off the wide portion of the blade.

The forms of the parts can be changed without departing from the gist of the invention as claimed.

10. What we claim is:

1. In a concrete mixing machine a mixing drum having a single charging and discharging opening, the bottom of said drum having curved and flat walls alternating with each other, and a blade in said drum consisting of a wide portion fixed in a position inclined to the wall of the drum adjacent to the opening thereof, and a narrow portion extending from said wide portion to near the bottom of the drum and curvally toward the axis of the drum, means for rotating said drum, and means for tilting the same.
2. In a concrete mixing machine, a mixing drum having a single charging and discharging opening, the bottom of said drum having curved and flat walls alternating with each other, and a blade in said drum consisting of a wide portion fixed in a position inclined to the wall of the drum adjacent to the opening thereof, a portion of said blade next the wall of the drum being bent in the direction of its motion, and a narrow portion extending from said wide portion to near the bottom of the drum, means for rotating said drum and means for tilting the same.
3. In a concrete mixing machine, a mixing drum having a single charging and discharging opening, the bottom of said drum having curved and flat walls alternating with each other, and a blade in said drum

consisting of a wide portion fixed in a position inclined to the wall of the drum adjacent to the opening thereof, and a narrow portion extending from said wide portion to near the bottom of the drum to a point near the junction of a curved and a flat wall thereof, said narrow portion being more offset from the wall of the drum than said wide portion of the blade, means for rotating said drum, and means for tilting the same.

4. In a concrete mixing machine, a mixing drum having a single charging and discharging opening, a blade in said drum consisting of a wide portion fixed in a position inclined to the wall of the drum adjacent the opening thereof, and a narrow portion extending from said wide portion to near the bottom of the drum, said narrow portion being more offset from the wall of the drum than said wide portion, means for rotating said drum, and means for tilting the same.

5. In a concrete mixing machine, a mixing drum having a single charging and discharging opening, a blade in said drum consisting of a wide portion fixed in a position inclined to the wall of the drum adjacent the opening thereof, and a narrow portion extending from said wide portion to near the bottom of the drum, means for rotating said drum and means for tilting the same, and means in the bottom of the drum for pressing the concrete material toward said opening of the drum when rotated in substantially horizontal position, said wide portion of the blade adapted to return the concrete material toward the bottom of the drum in such horizontal position.
